UNITED STATES PATENT OFFICE.

WILLIAM J. KENNEDY, OF ST. LOUIS, MISSOURI.

DEVICE FOR RETAINING BOOKS IN COVERS.

1,089,769.

Specification of Letters Patent. Patented Mar. 10, 1914.

Application filed November 18, 1912. Serial No. 732,126.

To all whom it may concern:

Be it known that I, WILLIAM J. KENNEDY, a citizen of the United States, and resident of St. Louis, Missouri, have invented certain new and useful Improvements in Devices for Retaining Books in Covers, of which the following is a specification.

This invention relates to devices for holding books in binders, and has for its object 10 to provide thin and stiffened strips of suitable material for this purpose insertible in the books, the strips with portions projecting through the backs of the books and adapted to be attached to posts, or the like, 15 of loose leaf binders.

Figure 1 is a perspective view of one of my devices. Fig. 2 is a perspective view of a book with one of my devices therein ready for application to a binder. Fig. 3 is a section 20 of a post binder and a book secured therein by one of my devices. Fig. 4 is a perspective view of a folder and one of my devices applied thereto. Fig. 5 is a section 25 of a number of book leaves and one of my devices showing one of the strip prongs for holding the leaves from movement.

My book holding device is made from a strip of thin material and comprises a body portion 6, having one of its edges turned 30 over or folded onto the body portion, thereby forming a stiffening rib 7. The said body portion is provided at its opposite edge with ears 8, provided with perforations 9, these 35 receive the posts 10, or the like, of a binder of the ordinary loose leaf type.

The body portion of my device is provided with prongs 11, stamped out of said portion, and bent upwardly or downwardly, 40 as found desirable, and which enter the leaves of the book, to hold the book against slippage on said body portion.

To place my device in service, the back 45 of the book to which the device is to be applied is slit, as indicated at 12, and the ears

8 are passed through the slits from the front to the back of the book and permitted to project as shown in Fig. 2; after this is done the ears are fitted to the posts 10 of the binder, and the book is thus held in position 50 between the binder covers 13.

If desired, I may corrugate the body portion 6 or stamp ribs from the material to stiffen the same, instead of turning the edge to produce the stiffening rib 7. 55

Having fully described my invention what I claim is:

1. A device for holding a book in a binder of loose leaf type, the said device comprising a body portion provided at one edge 60 with an extension adapted to project through the back of a book to provide for the connection of said device to the binder, the said body portion being provided with prongs adapted to enter a leaf of the book 65 to hold the book from movement relative to said body portion.

2. A device of the character described comprising a body portion, prongs formed thereon, perforated ears formed on the body 70 portion, which ears are adapted to project through the back of the book, to be supported on posts of a post binder, substantially as specified.

3. A device for holding a book in a loose 75 leaf binder, the said device consisting of a single leaf of thin sheet metal provided at its outer edge with a perforated extension adapted to be connected to the binder, the inner terminal edge of said single leaf of 80 thin sheet metal being folded to produce a single stiffening rib adapted to lie between the leaves of the book.

In testimony whereof, I have signed my name to this specification, in presence of two 85 subscribing witnesses.

WILLIAM J. KENNEDY.

Witnesses:

ALFRED A. EICKS,
W. C. STEIN.
